UNITED STATES PATENT OFFICE.

MASON C. MOODY, OF FAIRFIELD, ALABAMA.

AUTOMOBILE HEATER.

1,348,032.

Specification of Letters Patent. Patented July 27, 1920.

Application filed October 15, 1919. Serial No. 330,765.

To all whom it may concern:

Be it known that I, MASON C. MOODY, a citizen of the United States, residing at Fairfield, in the county of Jefferson, State of Alabama, have invented certain new and useful Improvements in Automobile-Heaters; and I do hereby declare the following to be a full, clear, and exact description of the invention, such as will enable others skilled in the art to which it appertains to make and use the same.

This invention relates to car heating apparatus, and more especially to heat radiators of that type intended for use as foot warmers; and the object of the same is broadly to utilize the exhaust gases from an internal combustion engine to heat the interior of the tonneau of a touring car or the body of a limousine.

The invention includes a branch pipe leading from the outlet or exhaust manifold, and a muffler cutout or switch for diverting the gases through this branch when it is desired to utilize them for heating the radiator.

A particular object of the invention is the production of a special and novel form of radiator whose flues or sections are provided with cores which will retain their heat for a considerable time after the flow of the heating fluid has been cut off.

One successful general arrangement of this heating apparatus and the specific construction of the radiator are described below and shown in the drawings in which:

Figure 1 is a diagrammatic plan view of a touring car equipped with this heating apparatus.

Fig. 2 is a horizontal section through the radiator, showing one of the cores also in section.

Fig. 3 is a cross section on the line 3—3 of Fig. 2.

The automobile has the usual engine E, floor F under the driver's feet, and tonneau X floor T. Beneath the latter is indicated a muffler M to which the exhaust manifold X leads from the engine cylinders, and the letter S designates broadly a muffler cutout or switch preferably located beneath the floor boards F which may be set to divert the gases through a pipe P to the radiator R which overlies the tonneau floor T (or might, in fact, be otherwise located within the tonneau), beyond which radiator the gases escape through the outlet pipe O. It will be obvious that the driver by manipu-

lating the switch S can direct the gases through the muffler, or cut them off from the muffler and divert them through the radiator, and the construction of the latter is such that a muffler will hardly then be needed to deaden the noise. The switch may be manipulated by a foot piece or handle H rising through a slot in the floor F.

Coming now to the details of the radiator and referring more especially to Figs. 2 and 3, I construct the same in a number of sections whereof three are shown herewith. Each section includes a tubular flue 1 coupled at its outlet end at 2 to a boss 3 which surrounds an opening 4 in one side of an outlet box 5 which extends transversely across the outlet ends of all the flues, one end being rounded at 6 adjacent the first flue and the other end 7 connected with the outlet pipe O. Internally also this box contains baffles 8 preferably curved as seen in Fig. 2 and employed to divert the gases which pass through the flues and deliver them along the box to its outlet 7, as also is the purpose of 80 the rounded end 6.

The inlet end of each flue engages a collar 10 to which in turn is connected a branch pipe 11, and the several branch pipes converge to a coupling 12 which is mounted on the inlet pipe P and internally divided by partitions 13 so that the gases flowing through said pipe will be broken up and fed in streams (three in the present instance) of substantially equal volume to and through the several flues. It is to be understood that I am not limited to the number of flues although I prefer several. In an extremely small radiator or foot warmer it might be possible to have but a single flue, but in that case I would prefer to make it oval or rectangular in cross section so that the entire radiator could be flat, whereas if there are several flues disposed side by side this general shape is secured. I have not thought it necessary to indicate the castings or brackets for supporting the radiator and spacing its sections.

Within each flue is a core which may well be a pipe of rather rough casting, and which is shown herein as having a tubular body 21 and a conical point 22 at the inlet end of the flue, the length of the core over all being such that when this point stands practically coincident with the collar 10, the open end 23 of the body stands near the opening 4 into the box. The body is to be

filled with a coarse granular material 24 such as broken stone, possibly interspersed with cast off pieces of metal, and as one successful means for holding this filling in place I pass pins or rods 25 through the core at the juncture of the body with the point and also through the body near its rear end 23, using at least two such pins at each point. The protruding ends of the pins contact with the inner face of the wall of the flue so that in effect they constitute a spider to hold the core centered within the flue and to leave an annular passage 26 through the latter for the flow of gases.

I find that when hot gases are employed as the heating agent and they are driven through the radiator sections in rapid successive pulsations, they heat both the shell or flue 1 of the section and the interior core; and if later the switch S is moved to cut out the radiator R and pass the gases out the muffler, the shells of the flue sections will quickly cool off a little but the cores will retain their heat for a considerable time and therefore keep the shells of the several sections warm which is precisely what is desired. In other words, the parts may be built of such sizes and the radiator of such capacity that the constant passage of the exhaust gases through the radiator would perhaps overheat it except in the severest weather, and at other times the occupants of the car would be kept quite comfortable if the radiator were put into use for a time and then cut out for a time. Because of this fact, it may be preferred that the switch shall be located beneath the tonneau floor T, or at least the handle or the foot piece H of the switch shall be extended so as to be within reach of the passengers rather than the driver; although this may be left to the builder.

What is claimed is:

1. The herein described radiator comprising

ing a plurality of sections, each consisting of a flue with a collar at its inlet end and a core along the axis of the flue, an inlet, branch pipes connecting it with the several collars, an outlet box connected with the outlet ends of the several flues, one end of the box being rounded toward the other end, and an exhaust pipe connected with the latter.

2. A sectional radiator for use as described, each section consisting of a flue with means for directing a heating fluid longitudinally throughout its length, a core consisting of a pipe containing a heat-retaining filling, and spiders for holding the core along the axis of the flue.

3. A sectional radiator for use as described, each section consisting of a flue with means for directing a heating gas longitudinally throughout its length, a core having a tubular body with its front end pointed and closed, a heat-retaining filling within said body, and spiders near the ends of the body holding the same centered within the flue.

4. A sectional radiator for use as described, each section consisting of a flue with means for directing a heating gas longitudinally throughout its length, a core consisting of a tubular body closed at that end adjacent the inlet of the flue and open at the other end, granular heat-retaining material within said body, and pins passing through the body and crossing each other in sets near the ends of the core for centering it within said flue and retaining the filling material.

In testimony whereof, I affix my signature in the presence of two witnesses.

MASON C. MOODY
